UNITED STATES PATENT OFFICE.

SAMUEL M. BADGER, OF ST. PAUL, MINNESOTA.

DRUM.

1,277,285.

Specification of Letters Patent. Patented Aug. 27, 1918.

Application filed May 17, 1916. Serial No. 98,066.

To all whom it may concern:

Be it known that I, SAMUEL M. BADGER, a citizen of the United States, residing at St. Paul, in the county of Ramsey and State 5 of Minnesota, have invented a new and useful Improvement in Drums, of which the following is a specification.

This invention relates to certain new and useful improvements in drums and is more 10 particularly designed to combine in the form of a single instrument the several devices of this character which are commonly used in the modern orchestra.

An object of this invention is to provide a 15 device of this type which is extremely efficient and durable and which is of comparative simplicity and economy in construction.

A further object is to provide tension means for the instrument whereby any one 20 of the batter-heads may be individually tuned or keyed as desired.

Another object is to so tension the several batter-heads that they may be jointly tuned or keyed by a single act and at the expenditure 25 of much less time than is ordinarily required with the modern drum or drums now in common use.

A still further object is to construct the instrument in such manner as to enable its 30 being knocked down and packed so that it will occupy a minimum amount of space for the purpose of shipment.

Other and further objects and advantages 35 of the invention will be hereinafter set forth and the novel features thereof defined by the appended claims.

In the drawings:

Figure 1 is a side elevation of the invention, partly in section and broken away 40 showing one manner of constructing the interior of the drum;

Fig. 2 is an enlarged detail of a portion of the single tensioning means employed, the shell of the drum being shown as broken 45 away;

Fig. 3 is a partial vertical section through the drum represented diagrammatically in Fig. 2.

Fig. 4 is a section taken on the line X—X 50 of Fig. 1.

In the drawings, the reference character A represents the shell of a drum of suitable size, over the opposite ends of which is stretched parchment *a* forming heads, counter hoops 1 and 2 being utilized for securing

the heads in position upon the retaining hoops 3 and 4, as is ordinarily done. The shell of the drum comprises a pair of frustums 5 and 6 of the male and female type, respectively, the reduced end of the male 60 frustum 5 terminating in an annular flange 7 provided with a bead 8 against which the reduced reinforced end of the female frustum 6 abuts when detachably secured in position about the flange 7, as shown. Each 65 of the frustums is reinforced by means of suitable ribs 9, which are attached upon the inner surface of the frustums.

As is customary, the drum is provided with a plurality of tension ropes spaced 70 equally thereabout and extending between the heads. In the present invention, however, each tensioning means comprises a rope passing about a sheave 10 having a hook 11 engaging the counter hoop carried upon one 75 frustum, the rope being bent to form parallel strands 12 and 13, the free ends of which pass through apertures 13' formed in the other frustum adjacent its head where they are suitably secured as by knotting. 80 As shown in Fig. 1, the manner of securing these ropes about the shell is alternated, that is to say, the hook sheave of one rope engages the hoop of one frustum, and the hook sheave of the next adjacent rope engages the 85 hoop of the other frustum. Annular wearing beads 14 and 15 are attached around the retaining hoops 3 and 4 respectively, over and against which the several ropes pass.

Securely fastened by screws or otherwise, 90 to the bead of the flange 7 is an outwardly projecting bracket 16 supporting at its free end a winch B comprising a skeleton frame 17 in which are journaled two drums 18 and 19 adapted for independent movement and 95 each of which has secured thereto a gear wheel 20 meshing with a short worm 21 journaled between ears 22 carried by the frame, a crank arm 27 (see Fig. 4) being connected to an end of each of the worms 100 whereby movement may be imparted to either of the drums desired.

Referring to Fig. 2, a rope or cable 23 having one end wrapped around and secured to the drum 18 is passed over one set of 105 strands 12 and 13, under the next adjacent set, and so on entirely around the drum, the free end of the cable 23 being then likewise wrapped about and secured to the drum 18 so that when the same is rotated by the crank 110

as aforesaid, the cable is further wound or unwound, as desired, to increase or decrease the tightening effect on the strands over which it passes so as to have a corresponding 5 effect on the particular parchment head associated with the counter hoop engaged by the hook sheaves of such strands. A second rope or cable 24 is similarly attached about the drum 19 and passes over the remaining 10 strands so as to enable the proper tensioning of the other of said parchment heads.

It may be stated that this invention contemplates other means than that explained for tensioning the heads. For instance the 15 rope forming the strands 12 and 13 may be looped about two sheaves each having a hook, similar to those 10 and 11, the ends of the rope joined tightly together, and the hooks engaged over the oppositely disposed 20 counter hoops 1 and 2. In this event, it is possible to use a winch having but a single drum 25 (see Fig. 4) journaled therein and about which one end of a single cable 26 is wrapped, the cable 26 passing over all of the 25 strands 12 and 13 spaced about the shell A, and having its free end secured to a short extension 20' from the winch. Under these conditions, the tension of the two opposite 30 parchment heads may be adjusted or regulated by a single movement of the drum 25 in the proper direction. If desired, small sheave wheels 27 may be provided on each of the strands 12 and 13 and the cables 23, 24 and 26, seated in grooves formed in the 35 periphery of each wheel to overcome friction.

In accordance with the patent statutes, I have described the principles of operation of my invention, together with the apparatus which I now consider to represent the 40 best embodiment thereof, but I desire to have it understood that the construction shown is only illustrative, and that the invention can be carried out by other means 45 and applied to uses other than those above set forth within the scope of the following claims.

Having described my invention, what I claim as new and desire to protect by Letters Patent is:—

1. A device of the type described comprising a shell having heads at its opposite ends, said shell consisting of a pair of frustums directly joined together at their 55 reduced ends, a plurality of tension cords secured at one end adjacent to the head of one of said frustums and at the other end having hooked engagement with the head of the other of said frustums, and means 60 passing about all of said cords for tensioning the same to produce a corresponding effect upon said heads.

2. A device of the type described comprising a shell having heads at its opposite 65 ends, said shell consisting of a pair of frus-

tums joined together at their reduced ends, a plurality of pairs of tension cords spaced about said shell, the alternate pairs of said cords being secured at one extremity adjacent to the head of one frustum and one extremity of the remaining pairs of cords being secured adjacent the head of the other frustum, the free ends of all of the pairs of cords engaging the head of the frustum remote from their several points of securance, 75 and means passing about said cords for tensioning the same, to produce a corresponding effect upon said heads.

3. A device of the type described comprising a shell having heads at its opposite 80 ends, said shell consisting of a pair of frustums joined together at their reduced ends, a plurality of pairs of tension cords spaced about said shell, the alternate pairs of said cords being secured at one extremity adjacent to the head of one frustum and one extremity of the remaining pairs of cords being secured adjacent the head of the other frustum, the free ends of all of the pairs of cords engaging the head of the frustum remote from their several points of securance, 85 and a single and continuously tensioning means passing laterally about said cords controlled from a single point for tensioning the same to produce a corresponding 90 effect upon said heads.

4. A device of the type described comprising a shell having heads at its opposite ends, said shell consisting of a pair of frustums joined together at their reduced ends, 100 a plurality of pairs of tension cords spaced about said shell, the alternate pairs of said cords being secured at one extremity adjacent to the head of one frustum and one extremity of the remaining pairs of cords being secured adjacent the head of the other frustum, the free ends of all of the pairs of cords engaging the head of the frustum remote from their several points of securance, 105 and means passing laterally about alternate pairs of said cords for tensioning the same 110 to produce a corresponding effect upon the head to which such alternate pairs of cords are attached.

5. A device of the type described comprising a shell having heads at its opposite ends, said shell consisting of a pair of frustums joined together at their reduced ends, a plurality of pairs of cords spaced about said shell, the alternate pairs of said cords 120 being secured at one extremity adjacent to the head of one frustum and one extremity of the remaining pairs of cords being secured adjacent the head of the other frustum, the free ends of all of the pairs of 125 cords engaging the head of the frustum remote from their several points of securance, and a plurality of separate means for tensioning each set of alternate pairs of cords independent of the other set of cords.

6. A drum comprising a pair of frustum shells separably and directly joined at their small ends and forming drum heads at their large ends, a plurality of cords extending longitudinally of and detachably coupled to said heads and means operable from a single point for contracting said aforesaid cords to hold said heads under tension and the small ends of said sections together. 15
- 5 7. A drum, comprising, a single pair of frustum shells, directly and detachably joined at their small ends and assisting in forming drum heads at their large outer ends, drum heads on the large ends of said shells and means for holding said heads on the outer ends of said shells under tension and for simultaneously holding said shells together. 20
- 10

In testimony whereof, I have signed my name to this specification.

SAMUEL M. BADGER.
